ARTIFICIAL HAND

Application filed December 6, 1928. Serial No. 324,157.

The object of the invention is to provide an artificial hand consisting of dual complementary fingers and an actuating wedge by which the fingers are swung towards and 5 away from each other, but wherein the fingers are pivotally mounted on a frame stationary with the arm carried member and the wedge movable with respect to such frame; to provide a device of the nature above indicated 10 in which the wedge is held yieldingly in retracted position (or closed position for the fingers) by a duality of resilient or elastic members of which one is mounted on each side of the wedge; to provide an artificial 15 hand having complementary fingers of which the terminals are disposed angularly to the shank portions and at the same time angularly with respect to the plane of movement of the fingers, so that a heavy object having a 20 handle or other means which may be grasped between the fingers will not, in having its weight sustained, impose a strain on the fingers in the direction of opening movement; to provide a construction of artificial hand in 25 which one of the fingers is provided with a hook simulating the function of the thumb on the human hand, said thumb hook being foldable down against the finger by which it is carried when not in use; and to provide in a 30 device of the kind indicated a construction in which the number of operating parts are reduced to a minimum and the structure thereby so simplified as to be susceptible of cheap manufacture and low marketing cost.

With this object in view, the invention consists in a construction and combination of parts of which a preferred embodiment is illustrated in the accompanying drawings, wherein:

Figure 1 is a side elevational view of a hand constructed in accordance with the invention.

Figure 2 is an edge elevational view.

Figure 3 is a top plan view.

Figures 4 and 5 are sectional views on the planes indicated by the lines 4-4 and 5-5 of Figure 2 respectively.

Figure 6 is a sectional view on the plane indicated by the line 6-6 of Figure 1, the folded position of the thumb hook being indicated in dotted lines.

The fingers A and B are pivotally mounted on a frame C of which the coupling D is made a part and constitutes the means for releasably connecting the hand with an arm stump member. The fingers are actuated to 55 open and close by means of a wedge member 10 of the general shape of an arrowhead, said wedge member being slidably mounted on a guide post 11 upstanding from the base 12 of the frame, the coupling member D being made 60 a part of the frame by virtue of connection with said base member. In addition to the base, the frame C comprises spaced plates 14 secured to the base on opposite sides by screws 15, one of the plates carrying posts 16 65 constituting the pivotal mountings for the fingers A and B. The posts are secured to the plate by which they are carried preferably by having reduced portions passed through the plate and peaned over against the outer face 70 of the latter. The posts are detachably connected with the remaining plate, having reduced portions entering eyes in the latter and the posts being drilled and tapped for the reception of screws 17. This construction 75 provides for the ready removal of one of the plates 14 after the removal of the post screws 17 and the corresponding base screws 15.

The base acts as a spacer between the plates at their lower ends and the posts as spacers 80 adjacent the upper end, the latter having the additional function of pivotal supports for the fingers.

The wedge 10 moves up and down between the body portions 18 of the fingers and the latter are provided with lateral extensible feet 19 and 20, the feet 19 bearing upon opposite sides of the double inclined nose of the wedge and the feet 20 on the double inclined heel portion of the same. The inclined surfaces of the nose portion are at a less acute angle than the inclined surfaces of the heel portion and the feet 19 are farther from the pivot points than the feet 20. This arrangement provides for ready opening of the fingers by movement of the wedge but precludes movement of the wedge by any force tending to open or spread the fingers, since in the former operation the sharp inclined surfaces of the nose may be readily employed to spread 100

the fingers, while in the latter operation, where the fingers are presumed to be the operating means, they are not effective in moving the wedge because of the slight inclination of the surfaces of the heel portion 5 thereof.

The wedge is held normally in a retracted position at which time the fingers are in closed relation, but the means for effecting the retracted position is yielding and consists of extensible members 21, preferably rubber bands, stretched over posts 22 and 23, the latter being mounted in the plates 14 and thereby being disposed on opposite sides of the frame, and the former being carried by the wedge and mounted on opposite sides of the latter, being permitted to move with the wedge by reason of the clearance slots 24 formed on the plates.

20 The extension of the wedge in opposition to the retracting means 21 is effected by a lever 25 rockingly mounted on a post 26 spanning the two plates and having a nose 27 engaging the end of the heel portion 21, the force arm of the lever having an eye 28 to which actuating means may be connected such for instance, as a cord passed up the sleeve of the user and anchored at the shoulder in any acceptable manner. The application of a pull on the cord as by the user extending the arm tensions the cord and thereby rocks the lever 25 and extends the wedge in opposition to the retracting means, thus effecting opening movement of the 35 fingers, their closing movement on the object to be grasped resulting when the pull on the lever actuating means is released because of the then following retraction of the wedge.

40 The shanks 29 and 30 of the two fingers are formed integral with the body portions 18 thereof and the hooks 31 and 32 are angular integral extremities of the shanks, these hooks being at slight acute angles to the 45 shanks and laterally deflected to lie in a plane diagonal to the planes of the plates 14. The shank 30 blends into the hook 32 with a slight curve and the shank 29 at its juncture with its hook 31 is formed with a heel portion 33 the curve between which and the shank 29 is similar to the curve connecting the shank 30 and hook 32.

55 Any object held between the fingers does not, by reason of the peculiar shape just described, impose any lateral strain tending to spread or open the fingers. If the object be held loosely as the bail of a bucket or handle of a basket, its weight is sustained by the hook 32 and that being disposed diagonally to the plane of the handle, the weight imposed by the object carried by the former effects no strain tending to spreading movement of the fingers, the shank 29 of the finger 60 A functioning merely to prevent lateral displacement of the bail or handle on the hook

32 of the finger B. The hooks 31 and 32 are complementary and when there is no object to be held between the fingers and the latter used merely as grippers for the movement of objects, the two hooks then serve 70 as a common hook, since they are held in close contact with the wedge in its retracted position.

An auxiliary thumb hook 34 is provided on the finger A, this being pivotally mounted between ears 35 formed on the finger and secured by a pin 36 straddling said ears. In the extended position shown, the thumb hook may serve as a support for the handle of a knife grasped between the hooks 31 and 32 80 when the latter are merely functioning as clamping members, as is frequently the case when tools and the like are to be held. When not desired for use, the thumb hook may be swung over to the folded position indicated in dotted lines.

The invention having been described what is claimed as new and useful is:

1. An artificial hand comprising a frame provided with means for connection to a 90 stump carried member, complementary fingers pivotally mounted on the frame, a wedge member mounted for movement axially of the frame and having a double inclined nose portion and double inclined heel portion, 95 said fingers having feet bearing on the inclined surfaces of the nose and heel respectively, resilient means normally retracting said wedge, and mechanical means for advancing said wedge.

2. An artificial hand comprising a frame provided with means for connection to a stump carried member, complementary fingers pivotally mounted on the frame, a wedge member mounted for movement axially of the frame, and having a double inclined nose portion and double inclined heel portion, 105 said fingers having feet bearing upon the inclined surfaces of the nose and heel respectively, resilient means normally retracting said wedge, and mechanical means for advancing said wedge, retracting means consisting of resilient members disposed on opposite sides of the frame and terminally secured to the frame and wedge respectively. 110

3. An artificial hand comprising a frame consisting of a base member and plates secured to opposite sides of said base member, posts spaced from the base member and spanning said plates, complementary fingers mounted for rocking movement on said posts, an actuating wedge slidably mounted in the frame between said posts and having a double inclined nose portion and double inclined heel portion, the fingers having feet bearing on the 125 inclined surfaces of the nose and heel portions respectively, yielding means for normally retracting the wedge and mechanical means for advancement of the wedge.

4. An artificial hand comprising a frame 130

consisting of a base member, plates secured to opposite sides of the base member, posts spaced from the base member and spanning said plates, a guide post upstanding from the base member between and in parallelism with the plates, a wedge slidably mounted on said guide post between the first said posts, complementary fingers rockingly mounted on the first said posts, the wedge having a double inclined nose with a double inclined heel portion and the fingers having feet bearing upon the inclined surfaces of the nose and heel portions of the wedge, yielding means normally retracting the wedge and mechanical means for advancing the wedge.

5. An artificial hand comprising a frame consisting of a base member, plates secured to opposite sides of the base member, posts spaced from the base member and spanning said plates, a guide post upstanding from the base member between and in parallelism with the plates, a wedge slidably mounted on said guide post between the first said posts, complementary fingers rockingly mounted upon the first said posts, the wedge having a double inclined nose with a double inclined heel portion and the fingers having feet bearing upon the inclined surfaces of the nose and heel portions of the wedge, yielding means normally retracting the wedge and mechanical means for advancing the wedge, and a lever rockingly mounted between the plates of the frame with one terminal exterior to the frame and the other in frictional contact with the end of the heel portion of the wedge.
